[57] CLAIM

The ornamental design for a urine sample container, as shown and described.

DESCRIPTION

FIG. 1 is a left front top perspective view of a urine sample container showing my new design;

FIG. 2 is a top plan view thereof;

FIG. 3 is a bottom plan view thereof;

FIG. 4 is a right elevational view thereof, the left elevational view being a mirror image thereof;

FIG. 5 is a front elevational view thereof; and,

FIG. 6 is a rear elevational view thereof.

FIG. 4
